(57) **CLAIM**

The ornamental design for a video game console wall mount, as shown and described.

DESCRIPTION

FIG. 1 is a front, right and top perspective view of a video game console wall mount, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an exploded view of the video game console wall mount; and,

FIG. 9 is an enlarged view of an encircled portion of the video game console wall mount labeled 9 in FIG. 1. The evenly-dashed broken lines shown in the drawings encircling portions of the video game console wall mount illustrated in enlargements form no part of the claimed design.
